UNITED STATES PATENT OFFICE.

ALFRED GRIEB, OF ELIZABETH, NEW JERSEY, ASSIGNOR TO THE SINGER MANUFACTURING COMPANY, A CORPORATION OF NEW JERSEY.

FEEDING MECHANISM FOR SEWING-MACHINES.

1,111,829.

Specification of Letters Patent. Patented Sept. 29, 1914.

Application filed November 18, 1913. Serial No. 801,572.

To all whom it may concern:

Be it known that I, ALFRED GRIEB, a citizen of the United States, residing at Elizabeth, in the county of Union and State of New Jersey, have invented certain new and useful Improvements in Feeding Mechanisms for Sewing-Machines, of which the following is a specification, reference being had therein to the accompanying drawings.

5 This invention relates to feeding mechanism for that class of sewing machines adapted more especially for basting and the like, in which intermittent feeding movements are imparted to the work by a toothed feed-wheel.

10

15

In the present construction the machine is provided with the usual reciprocating needle and spring-pressed presser-bar, the latter being provided at its lower end with a carrier formed with depending spaced arms which support the shank of a yielding presser-foot. The yoke formed by the spaced depending arms of said carrier serves to confine a channeled bearing sleeve to receive one end of a rotary shaft for the feed-wheel, said sleeve normally resting upon the shank of the presser-foot under the action of a spring fitted in a socket formed in the carrier intermediate said arms. The opposite end of the rotary shaft is journaled in a bearing member pivotally supported above the bed-plate, and is provided with a ratchet-wheel which is engaged by a pawl actuated from a rock-shaft operatively connected with the driving shaft of the machine.

20

25

30

35

The feeding movements are controlled by a manually operated arm having a cam surface adapted to engage a pin carried by the actuating pawl, whereby the latter is held out of engagement with the ratchet-wheel during a portion of this movement; and means comprising a movable plate are provided for modifying the cam surface of said arm. The presser-bar is provided with the usual lifting rock-lever, and a treadle-rod connected to the latter carries a laterally extending member adapted to engage the pawl-controlling arm, whereby said arm may be operated by the lifting treadle for the presser-bar. A spring is provided for returning said arm to neutral position upon its release.

40

45

50

55

It will be seen that the feed-wheel is movable with and also independently of the

presser-bar and presser-foot, and that the movements of said wheel may be modified at will within a considerable range of adjustment.

In the accompanying drawings, Figure 1 is a rear side view of a sewing machine provided with the present improvements and Fig. 2 is a front elevation of the same. Fig. 3 is a perspective view of the actuating members for the upper feed-wheel. Fig. 4 is a sectional view of the machine on line *a a* Fig. 1. Fig. 5 is a perspective view of the presser-foot and its carrier.

As represented in the drawings, the invention is shown in connection with a sewing machine constructed with the bed-plate A, hollow standard B and overhanging arm C, in which is journaled the main-shaft 1 carrying at its outer end the balance wheel 2 and grooved belt-pulley 3. In the head of the overhanging arm C is journaled the usual reciprocating needle-bar 4 carrying needle 5, and the presser-bar 6 provided with collar 7 secured to said bar by means of screw 8 and serving to limit the movement of the bar under the action of a spring 9 surrounding the bar intermediate the hub 10 of a lateral arm 11, secured to said bar by means of screw 12, and the upper portion of the bracket-arm.

The feeding members comprise a lower toothed feed-wheel 13 and a positively driven upper toothed wheel 14. The lower feed-wheel is mounted upon shaft 15 journaled within the hub 16 of a bracket 17 secured within a depression 18 formed in the bed-plate A, by means of screws 19. The feed-wheel 13 projects above an aperture 20 formed in the throat-plate 21.

To the lower end of presser-bar 6 is secured by means of screw 22 the laterally extending shank 23 of a carrier for the presser-foot, said carrier being provided with spaced depending arms 24 adapted to support the shank 25 of a presser-foot 26, said shank being secured to the arms by means of screws 27. The presser-foot 26 is pivotally connected to its shank by means of a pin 28, and a light pressure is maintained upon said foot by means of a wire spring 29 secured to the shank 25 by means of screw 30, its other end entering an aperture 31 formed in the presser-foot.

The upper feed-wheel 14 is carried by a rotary shaft 32 being fixed against move-

ment thereon by means of screw 33. The outer end of shaft 32 adjacent feed-wheel 14 is journaled within a bearing sleeve 34 formed with oppositely disposed channels 35 which receive the depending spaced arms 24 of the presser-foot carrier, said boss normally resting upon the upper face of the presser-foot shank 25 under the pressure of a spring 36 seated within a socket formed 5 within the head of the carrier intermediate arms 24. The opposite end of rotary shaft 32 is journaled within the hub of a bearing member 37 provided with a lateral stud 38 by which said bearing member is pivotally 10 supported within the sleeve 39 of a standard 40 formed with a base portion 41 secured upon the upper face of the bed-plate A by means of screws 42. The stud 38 is confined within sleeve 39 by means of a 15 collar 43.

The driving means for feed-wheel 14 comprise a ratchet-wheel 44 provided with a hub 45 secured in fixed position upon shaft 32 by means of screw 46. Journaled upon 20 shaft 32 intermediate ratchet-wheel 44 and the hub of the bearing member 37 is the hub of a plural-armed lever 47, its upper arm being provided with an aperture to receive stud 48 overhanging ratchet-wheel 44 25 and supporting the pawl 49 pressed downwardly by coil-spring 50 to engage the teeth of said ratchet-wheel. The lower arm 51 of rock-lever 47 is secured by means of screw 52 to one end of a link 53, the opposite end 30 of said link being secured by means of screw to upwardly extending crank-arm 56 provided with a hub 57 secured by means of a screw 58 upon a shaft 59 adapted to rock below the bed-plate upon pivot studs 59.

Upon rock-shaft 59 is secured by means of screws 61 the hub 62 of a laterally extending arm 63 provided with a segmental slot 64 to receive a stud bolt 65 clamped within a split collar 66 at the lower end of pitman 45 67, the latter extending upwardly through the standard B and being provided with straps to embrace an eccentric 68 upon main-shaft 1. It will be seen that the adjustment of pitman 67 with respect to arm 63 will regulate the normal length of movement of crank-arm 56 and consequently, 50 through rock-lever 47 and pawl 49, modify the feeding movement imparted to feed-wheel 14.

A controlling device is provided for actuating-pawl 49. Said device comprises an arm 69 provided with a finger-lever 70, said arm being pivoted by means of stud 71 to a bracket 72, said bracket being provided 60 with a base portion 73 secured upon the upper face of bed-plate A by means of screws 74. The arm 69 is provided with a cam surface 75 normally disposed in a neutral position relative to pin 60 carried by actuating pawl 49, under the action of a spring

76 having one end secured to finger-lever 70 by means of the screw 77 and its other end entering an aperture formed in the bracket 72. In its neutral position the arm 69 permits pawl 49 to engage the teeth adjacent thereto at the beginning of its forward movement and thus to impart a maximum feeding movement to the feed-wheel 14 for the formation of a long basting stitch. When, however, the finger-lever 70 is depressed against the action of the spring 76, the cam surface 75 of the arm 69 is elevated to engage pin 60 and lift pawl 49 so that the latter on its forward stroke will ride above the ratchet-teeth until its pin 80 passes the cam surface of the arm, at which point the pawl is permitted to engage a tooth of the ratchet-wheel and thereby effect a short movement of the feed-wheel. The movement of the pawl controlling arm 85 is limited by means of a stop-screw 81 the shank of which passes through a slot formed in the arm above stud 71 being supported by bracket 72. The cam surface of arm 69 may be modified to increase or decrease its 90 action upon pawl 49 by means of a sliding plate 78 provided with a segmental slot 79 through which passes a screw 80 by which the plate is adjustably secured to cam arm 69. 95

Lateral arm 11 secured to presser-bar 6 is adapted to support an upwardly extending link 82 formed with a longitudinal slot 83 to receive the reduced end 84 of a lifting lever 85 fulcrumed by means of stud-screw 86 upon the overhanging arm C of the sewing machine. The opposite end of the lifting rock-lever 85 is connected by means of screw 87 with treadle-rod 88 having its lower end formed with a hook 89 to receive chain 90 which in practice is connected to a suitable treadle. Upon the treadle-rod 88 is fixed a collar 91 to the upper face of which is secured by means of screw 92 a laterally extending spring arm 93, the outer end of which overhangs finger-lever 70 of pawl-controlling arm 69. It will be seen that a limited movement of treadle-rod 88 will, through arm 93, elevate the cam surface of pawl-controlling arm 69 to decrease the length of feeding movement, and this without affecting the presser-bar, inasmuch as the reduced end 84 of lifting rock-lever 85 is permitted to move within the slot 83 of arm 82 which serves to transmit lifting movements to the presser-bar. 115

It will be understood that the scope of the present invention is not limited to the specific embodiment thereof herein shown and described, it being evident that the various parts thereof may be widely varied both in construction and arrangement. 125

Having thus set forth the nature of the invention what I claim herein is:—

1. In a sewing machine, the combination 130

- with a driving shaft and stitch-forming mechanism, of a spring-pressed bar and lifting means therefor, a carrier supported by said bar, a presser-foot connected to said carrier, a feed-wheel provided with a shaft mounted at one end within said carrier to move with the same, a movable support for the opposite end of said shaft, and actuating means operatively connecting the driving shaft and said feed-wheel whereby intermittent movements are imparted to the latter. 50
2. In a sewing machine, the combination with a driving shaft and stitch-forming mechanism, of a spring-pressed bar and lifting means therefor, a carrier supported by said bar, a presser-foot connected to said carrier, a feed-wheel provided with a shaft mounted at one end within said carrier and yielding relatively to the same, a movable bearing member for the opposite end of said shaft, a ratchet-wheel carried by the latter, an actuating pawl, and operative connections between the driving shaft and said pawl, whereby intermittent movements are imparted to the feed-wheel. 55
3. In a sewing machine, the combination with stitch-forming mechanism, of a spring-pressed bar, a stop to limit the movement of the latter under the action of its spring, a carrier supported by said bar, a presser-foot pivotally connected to said carrier; a spring for said presser-foot, a feed-wheel provided with a shaft mounted at one end within and yielding relatively to said carrier, a spring within the latter and engaging said shaft, a movable support for the opposite end of said shaft, actuating means for the feed-wheel, and a lifting device for the presser-bar. 70
4. In a sewing machine, the combination with stitch-forming mechanism, of feeding mechanism comprising a feed-wheel and a yielding support for the same, actuating means for said wheel including a ratchet device and an actuating pawl therefor, a member adapted to be moved into effective position to vary the action of said pawl, and automatically acting means for returning said member to a neutral position. 75
5. In a sewing machine, the combination with a stitch-forming mechanism, of feeding mechanism comprising a feed-wheel and actuating mechanism therefor, a presser-foot, means including a treadle-rod for lifting said presser-foot, controlling means for said actuating mechanism, and connections between said controlling means and the treadle-rod whereby movement of the latter will modify the feeding movements of said wheel. 80
6. In a sewing machine, the combination with stitch-forming mechanism, of feeding mechanism comprising a feed-wheel, actuating means for said wheel including a ratchet device and an actuating pawl therefor, an arm provided with a cam surface adapted to render said pawl ineffective during a portion of its movement, means including a movable plate for modifying the cam surface of said arm, and means for moving said arm into neutral position. 85
7. In a sewing machine, the combination with stitch-forming mechanism, of feeding mechanism comprising a feed-wheel and a rotary shaft therefor, a ratchet-wheel on said shaft, an actuating pawl engaging the teeth of said ratchet-wheel, a pin carried by said pawl, a pivoted arm having a cam surface adapted to engage the pin to lift said pawl, means for moving said arm into effective position, and automatically acting means to return said arm to a neutral position. 90
- In testimony whereof, I have signed my name to this specification, in the presence of two subscribing witnesses. 85
